WRENCH FOR REMOVING THE BACKS OF
WATERPROOF WATCHES

Lloyd Ghiglieri, Oakland, Calif.

Application March 27, 1945, Serial No. 585,042

2 Claims. (Cl. 81—6)

1

This invention relates to improvements in wrenches.

An object of my invention is to provide an improved wrench having a number of relatively adjustable jaw members which are arranged for engagement with devices of different sizes and shapes.

Another object of my invention is to provide an improved wrench having a number of angularly arranged jaw members which are capable of being relatively adjusted to different positions, whereby the wrench may be used to engage with devices of different sizes and shapes, as for instance, the screwable backs of various types of waterproof watch cases.

A further object of my invention is to provide an improved wrench of the kind characterized, having novel means for mounting a number of adjustable jaw members whereby different sets of such members may be conveniently substituted one for another to permit the use of the wrench with waterproof watch cases or other devices having different shapes or constructions.

Other and further objects of my invention will be pointed out hereinafter, or will be indicated in the appended claims, or will be obvious to one skilled in the art upon an understanding of the present disclosure. For the purpose of this application I have elected to show herein certain forms and details of a wrench representative of my invention; it is to be understood, however, that the embodiment of my invention herein shown and described is for the purpose of illustration only, and that therefore it is not to be regarded as exhaustive of the variations of the invention, nor is it to be given an interpretation such as might have the effect of limiting the claims, short of the true and most comprehensive scope of the invention in the art.

In the accompanying drawings:

Fig. 1 is a plan view of a wrench embodying the preferred principles of my invention;

Fig. 2 is a side elevation of the wrench, showing diagrammatically, by the broken lines, a watch case engaged by the adjustable clamping jaws;

Fig. 3 is a bottom view of the wrench, showing diagrammatically, by the broken lines, the watch case and the adjustable clamping jaws engaging therewith;

Fig. 4 is a sectional view taken on the line 4—4 of Fig. 1;

Fig. 5 is an end view of the wrench;

Fig. 6 is a sectional view taken on the line 6—6 of Fig. 7;

2

Fig. 7 is an enlarged sectional view taken vertically through one of the clamping jaws; and

Fig. 8 is a perspective view of one of the clamping jaws.

Referring to the drawings, the numeral 1 designates a shank having one of its ends threaded and its opposite end positioned between and secured by screws 2 to upper and lower supporting plates 3 and 4. Pivoted connected to the supporting plates, as at 5' and 6', are two pairs of arms 5 and 6, the upper arm of each pair being positioned between the upper and lower supporting plates 3 and 4, and the lower arm of each pair being positioned beneath the lower supporting plate 4.

Rotatably carried at the outer ends of the pairs of arms 5 and 6, respectively, are jaw supporting members 7 and 8 which are each provided with end openings or sockets for receiving removable jaws 9. As shown in Fig. 7, the jaw supporting members 7 and 8 embody an assembled structure comprising an inner tube 10 which carries a spring pressed ball 11 that engages with a jaw 9 and normally holds the latter in the socket in tube 10. A sleeve 12 positioned around the lower part of tube 10 engages with the spring which urges the ball 11 into firm engagement with the jaw 9. The upper part of the tube 10 is externally threaded and passes through the outer ends of arms 5 and through an intermediate nut 13 which holds a small pin 14 in an annular groove 13' in the lower end of a pivoted post 15. The annular groove 13' is intersected by a vertical groove 13a which permits the small pin 14 to be lodged in the annular groove 13' when the parts of the jaw supporting member are assembled. By turning the post 15 through a certain angle the groove 13a is moved to a position where it cannot receive the pin 14, thus preventing the post from being detached from tube 10, but still allowing it to turn inside the said tube. The same structure is provided with respect to the other jaw supporting member 8.

The body portion of each of the jaws 9 are of general cylindrical shape and each is formed at one or both ends with shoulders or the like for engaging with a device to be rotated or firmly held, as for instance the removal part A of a waterproof watch case. It is contemplated that the jaws 9 or others like them be provided with differently shaped and constructed ends so as to permit the use of the wrench with devices, slots or notches of different shapes and constructions. The upper ends of the posts 15 are provided with diametrically disposed threaded openings,

and operatively engaging therewith is an adjusting screw 16 having its opposite ends provided with left hand and right hand threads. Centrally secured to the screw 16 is a knurled disc 17 which when turned in one direction rotates the screw to actuate the free ends of the opposed pairs of arms 5 and 6 away from each other, and when turned in the opposite direction rotates the screw to actuate the pairs of arms about their pivots toward each other. Thus the jaws 9 may be adjusted toward or away from each other to suitably position them for engagement with elements of different shapes or sizes. The disc 17 rotatably extends through a slot in an end of the upper supporting plate 3, and its periphery is disposed where it can be conveniently engaged for manipulation by an operator's thumb.

Loosely mounted on the shank 1 is a tubular handle 18 which is secured at its forward end to an elongated plate 19. The forward end of the plate 19 carries a jaw supporting member 20 which has a jaw 21 detachably carried thereby. The jaw 21 is similar to the other jaws 9 and 9, and it provides a third member for engaging with an element to be rotated or firmly held. The jaw supporting member 20 has an upper extension 20' which slidably extends through a slot 4' located in the lower supporting plate 4, the said slot being arranged so its opposite sides guide the jaw supporting member 20 along a fixed path toward and away from a plane passing vertically through the jaws 9 and 9.

Threaded on the end of the shank 1 is an adjusting sleeve 22, which interiorly carries a nut 22' (see Fig. 4) that engages with the right hand threads on the outer end of the said shank. The adjusting sleeve is also internally threaded as at 22a, the latter threads being in engagement with the left hand threads provided on the tubular handle 18. Thus by turning the sleeve 22 to the right the tubular handle 18 and the jaw 21 are moved inwardly, and when turned in the opposite direction the said tubular handle and the said jaw are actuated in the opposite direction.

By the adjustment of the jaws 9, 9, through the manipulation of the disc 17, and the adjustment of the jaw 21 by means of the adjusting sleeve 22, the said jaws may be relatively adjusted to engage with devices or elements of different sizes or shapes. By substituting one set of jaws for another set having different shapes and constructions, the wrench may be used to unscrew or hold removable backs of watch cases of different makes. Similarly, by employing jaws or other types of engaging members, the wrench may be satisfactorily used for various other purposes. It is therefore to be understood that the term "jaw" as herein employed shall be construed to include pins, sockets, or other types

of engaging members adapted to connect with or fasten to different devices or elements.

What I claim is:

1. In a wrench, a supporting structure having a pair of relatively adjustable jaws mounted at one end and a threaded shank secured to its other end, means for adjusting the jaws with respect to one another, an adjustable tubular handle member slidably mounted on the shank and having one end threaded and its opposite end formed with an extension, a third jaw carried by the extension, and an internally threaded sleeve extending around the threaded end of the shank and having two distinctive sets of threads engaging, respectively, with the threads of the shank and the threads of the tubular handle member, whereby when the sleeve is rotated the tubular handle member is moved to adjust the third jaw with respect to the other two jaws.
2. In a wrench, a supporting structure comprising an upper plate and a lower plate provided with a guide slot, lever arms pivotally mounted on the supporting structure, each supporting a jaw carrying member, means for adjusting the lever arms with respect to each other whereby the jaw carrying members may be relatively adjusted, a shank secured at one end to the upper and lower plates and having its other end provided with right hand threads, a tubular handle member adjustably mounted on the shank and having left hand threads at one end and an extension on its opposite end, a third jaw carrying member secured to the shank's extension and having an extension slidably positioned in the guide slot of the lower plate of the supporting structure, and an internally threaded sleeve having two distinctive sets of threads, one set engaging with the left hand threads of the tubular handle member and the other set engaging with the right hand threads of the shank, whereby the tubular handle member may be moved, when the sleeve is turned, to adjust the third jaw carrying member with respect to the other jaw carrying members.
